Hand

Front plate of a Parlor Stove,
and Ezra Ripley, of Troy, N. Y.
Putter & Co., of the same place.

Des 982

Patented Jan'y 12. 1858.

Des. 982

N. S. Vedder & Ezra Ripley, of Troy N.Y.

Assignors to

L. Patter & Co. of same place.

Letters Patent No 982. Dated Jan: 12th 1858.

The schedule referred to in these letters patent & making part of the same.

To all whom it may concern:

Be it known that we N. S. Vedder and

Ezra Ripley, each of the City of Troy in the County of Rensselaer and state of New York, have jointly invented or produced a new & original Design for the Front-plate of a Parlor-Stove; and we do hereby declare that the following is a full and exact description of the same reference being had to the annexed photographic drawing making a part of this specification. —

Our ornamental design for the front-plate of a Parlor-Stove is composed of the swelling chick-work body, a, enclosed by curved moldings, b, b, which, at the middle of the bottom, are covered by the corrugations, c, and plumes, d; at the top, terminate in the twin double-scrolls, e, e; and at the sides, expand into the broad scrolls, f, f, & g, g; which latter sets of scrolls, as well as the plumed side moldings, h, h, are pierced by the bundled columns, i, i, — all as shown in the annexed photographic drawing of a front plate. —

What we claim as our invention or production and desire to secure by Letters Patent, is the ornamental design herein described and shown in the annexed drawing, for the front plate of a parlor-stove.
